(57) CLAIM

The ornamental design for a protective covering for video game and associated accessories, as shown and described.

DESCRIPTION

FIG. 1 is a front elevational view of a protective covering for video game and associated accessories showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines are for illustrative purpose only and from no part of the claimed design.
